(57) **CLAIM**

The ornamental design for an uninterruptible power supply, as shown and described.

DESCRIPTION

FIG. 1 is a front perspective view of an uninterruptible power supply showing our design;

FIG. 2 is a front view thereof;

FIG. 3 is a rear view thereof;

FIG. 4 is a side view thereof;

FIG. 5 is a side view thereof, opposite that shown in FIG. 4;

FIG. 6 is a top view of the uninterruptible power supply;

FIG. 7 is a bottom view thereof;

FIG. 8 is a front perspective view of another embodiment of the uninterruptible power supply showing our design;

FIG. 9 is a front view thereof;

FIG. 10 is a rear view thereof;

FIG. 11 is a side view thereof;

FIG. 12 is a side view thereof, opposite that shown in FIG. 11;

FIG. 13 is a top view of the uninterruptible power supply; and,

FIG. 14 is a bottom view thereof.

The broken lines in the drawings illustrate portions of the uninterruptible power supply that form no part of the claimed design.
